UNITED STATES PATENT OFFICE.

JOHN M. CAGE, OF SANTA MONICA, CALIFORNIA, ASSIGNOR, BY MESNE ASSIGNMENTS,
TO HALVOR ANDRESEN, OF CHRISTIANIA, NORWAY, AND OLIVER OTIS HOWARD,
OF ROCKPORT, MASSACHUSETTS.

SLEEVE-VALVE ENGINE.

Application filed August 25, 1921. Serial No. 495,168.

To all whom it may concern:

Be it known that I, JOHN M. CAGE, a citizen of the United States, residing at Santa Monica, in the county of Los Angeles and State of California, have invented new and useful Improvements in Sleeve-Valve Engines, of which the following is a specification.

This invention relates to internal combustion engines, particularly of the type using a sleeve valve; and furthermore particularly of the type utilizing a pressure feed for the combustible charge. Such type of engine is usually, although not necessarily, a two-cycle engine; and for those reasons I here illustrate and describe my invention as applied to a two-cycle engine using a sleeve valve and having its charge fed to the valve and to the cylinder under pressure.

In engines where the charge is drawn into the cylinder by piston suction, a slight amount of leakage into the cylinder around the sleeve valves is of no great consequence, so long as that leakage is uniform. However, where the charge is fed under pressure to the valves, the leakage around the valves causes considerable waste of fluid. It is a general object of this invention to provide means for overcoming such leakage and preventing the consequent waste. Other objects and corresponding features of the invention will be best understood from the following detailed description of the invention as applied specifically to a two-cycle sleeve-valve engine; reference for this purpose being had to the accompanying drawings in which—

Fig. 1 is a vertical cross-section of such an engine equipped with my invention; and Fig. 2 is a vertical longitudinal section of the same.

In the drawings I illustrate a water-cooled cylinder structure at C in which piston P is adapted to reciprocate, the piston being connected by the connecting rod 10 to the crank of the engine shaft 12. Piston P carries a sleeve S preferably integral with the piston, and extending upwardly therefrom, the upper end of the sleeve extending into an annular space between the cylinder wall and a depending head 15. The cylinder charge intake, scavenging and exhaust ports, 16, 17 and 18 respectively, are adapted to be uncovered by corresponding

sleeve ports 16^a, 17^a and 18^a, as the piston 55 nears the lower end of its stroke. The ports are so sized that the exhaust port 18 is uncovered first, so as to relieve the exhaust pressure; and then the scavenging air ports 17 and then the charge ports 16 are uncovered, allowing the air to flow into and through, and the charge to flow into the combustion chamber, ready for compression as the piston moves upwardly. In this particular case I have illustrated this charge 60 as coming to the intake port through a manifold 20 connected with a carbureter 21 which is fed with air under pressure through a pipe 22 that connects with the outlet of a blower B which is driven from the engine 65 shaft. The peculiar properties and actions of this blower B I have spoken of in other co-pending applications Ser. No. 398,329, filed July 23, 1920; Ser. No. 495,166 and Ser. No. 495,167, filed August 25, 1921; so far as 70 the present invention is concerned, it suffices merely to say that the blower B raises a pressure and delivers air under pressure to the carbureter from whence a mixture 75 under pressure is delivered to the charge 80 intake port 16. I have also explained in my said co-pending applications how fuel and a charge of air, under pressure, may be introduced separately to the cylinder; the air pressure also being raised by such a 85 blower as herein illustrated; and then the fuel being introduced from the carbureter which is supplied with such air under pressure, or being introduced by injection or other positive introduction means. For instance a branch pipe 22^a may lead from air pressure pipe 22 to the scavenging air ports 17, whereby these ports are fed with the air under pressure. This arrangement is explained for instance in application Ser. No. 90 495,167. All such specific arrangements 95 may be made within my present invention; but it will be understood that the situation to which my invention is applied is, generally speaking, a situation in which a charge is introduced to such an engine as herein described under pressure, whether that charge be a charge of pure air or a charge of carbureted air. It 100 is of course most important to prevent leakage of a charge of carbureted air, to prevent loss of fuel.

In order to prevent such loss of fuel, I

locate a cylinder wall groove 25 above intake ports 16, and another cylinder wall groove 26 below the intake ports 16. These two cylinder wall grooves (which may be interconnected by grooves 27 longitudinal of the cylinder) I supply with air under pressure through a tube 28 that connects up with the air pressure pipe 22; so that these grooves are at all times supplied with air 10 under a pressure equal to or greater than that under which the carbureted charge is fed to the intake port 16, and thus equal to or greater than that pressure under which leakage can take place between the outer surface 15 of the sleeve S and the cylinder wall. It will be apparent that the pressure on the charge at the port 16 can never be greater than that in the pipe 22; nor greater than that in the grooves 25 and 26; because the size of the 20 connection to these grooves from the pipe 22 is ample to supply the small leakage of air that may occur; while the pressure may normally be less at the port 16 than at the grooves 25 and 26 because under most 25 circumstances the controlling throttle 30 of the carburetor will be but partially open, and also because the tube 28 connects to pipe 22 below the Venturi tube V of the carburetor. Thus, the leakage of air from the groove 25 30 will meet and oppose the leakage of mixture or liquid from the port 16, and effectually counteract that leakage. In fact, under most circumstances, there will be a slight leakage of air from the grooves 25 and 26, 35 to the port 16, rather than a leakage of the carbureted mixture or liquid away from the port. In case any fuel should leak into the grooves 25 or 26 I provide a tube 28 which drains downwardly and may enter the 40 float chamber of the carburetor 21.

Lower down on the cylinder there are two oil grooves 38 into which (through connections indicated at 38') lubricant may be introduced to lubricate the sleeves and the pistons. Above these grooves there is a groove 39 which is adapted to pick up any excess of oil which might otherwise move upwardly on the sleeve and get into the intake ports, returning this excess of oil through 45 tubes 40 to the crank case. Between the oil return groove 39 and the groove 26 there is another air pressure groove 35 fed with the same air pressure as before mentioned through tube 37 from pipe 22. This groove, 50 like grooves 38 and 39, extends completely around the cylinder walls; and its function is to oppose in pressure to the downward carriage of fuel by the sleeve moving downwardly and to the upward carriage of lubricant by the sleeve moving upwardly from 55 the lubricated zone.

Having described a preferred form of my invention, I claim:—

1. In combination with an internal combustion engine having a cylinder and intake

port and a sleeve valve movably fitting within the cylinder controlling said intake port; means for maintaining an air pressure around said intake port in the space between the sleeve and the cylinder wall. 70

2. In combination with an internal combustion engine having a cylinder and an intake port and a sleeve valve movably fitting within the cylinder controlling said intake port; means for feeding a charge to said intake port under pressure, and means for maintaining a seal around said intake port in the space between the sleeve and the cylinder wall. 75

3. In combination with an internal combustion engine having a cylinder and an intake port and a sleeve valve movably fitting within the cylinder controlling said intake port; means for feeding a charge of carbureted air to said intake port under pressure, and means for maintaining a seal of air around said intake port in the space between the sleeve and the cylinder wall. 80

4. In combination with an internal combustion engine having a cylinder and an intake port and a sleeve valve movably fitting within the cylinder controlling said intake port; means for feeding a charge to said intake port under pressure, and means for maintaining a counter pressure around said intake port in the space between the sleeve and the cylinder wall, said last mentioned means embodying grooves in the cylinder wall on opposite sides of said intake port, and means for introducing air under pressure to said grooves. 90

5. In combination with an internal combustion engine having a cylinder, an intake port, and a sleeve valve movably fitting within the cylinder controlling said intake port; means to raise and maintain an air pressure, a carburetor fed with said pressure air and communicating with said intake port to feed carbureted air to said port; and means for introducing said air pressure to the space between the sleeve and the cylinder wall around said intake port. 105

6. In combination with an internal combustion engine having a cylinder, an intake port, and a sleeve valve movably fitting within the cylinder controlling said intake port; means to raise and maintain an air pressure, a carburetor fed with said pressure air and communicating with said intake port to feed carbureted air to said port; and means for introducing said air pressure to the space between the sleeve and the cylinder wall around said intake port, said last mentioned means embodying grooves in the cylinder wall on opposite sides of said intake port, and a passage by which said pressure air is introduced to said grooves. 115

7. In combination with an internal combustion engine having a cylinder and intake port, and a sleeve valve movably fitting 120

- within the cylinder controlling said intake port; means for maintaining an air pressure around said intake port in the space between the sleeve and the cylinder wall, means for supplying oil to the sleeve below said pressure maintaining means, and a relief groove in the cylinder between the pressure maintaining means and the zone in which oil is applied to the sleeve.
10. 8. In combination with an internal combustion engine having a cylinder, an intake port, and a movable sleeve valve in the cylinder controlling said intake port; means to raise and maintain an air pressure, a carburetor fed with said pressure air and communicating with said intake port to feed carbureted air to said port; and means for introducing said air pressure to the space between the sleeve and the cylinder wall around said intake port, said last mentioned means embodying grooves in the cylinder wall on opposite sides of said intake port, and a passage by which said pressure air is introduced to said grooves; means to lubricate said sleeve at a zone below said cylinder groove, and a groove located between said cylinder grooves and the lubricating zone.
9. In combination with an internal combustion engine having a cylinder, a piston, and an intake port, a movable sleeve valve within the cylinder and having a port controlling the said intake port; a head extending down within said sleeve, the intake port being near the lower end of said head; means to cause reciprocation of said sleeve from a lower position in which the intake port is opened to an upper position in which the sleeve port passes entirely into the space between the cylinder wall and the depending head whereby said sleeve port is sealed during the compression and explosion strokes of the engine; means for introducing a charge of carbureted air to said intake port under pressure, and means for maintaining an air pressure in the space between the sleeve and the cylinder wall around said intake port.
10. In combination with an internal com-

bustion engine having a cylinder, a piston, and an intake port, a movable sleeve valve within the cylinder and having a port controlling the said intake port; a head extending down within said sleeve, the intake port being near the lower end of said head; means to cause reciprocation of said sleeve from a lower position in which the intake port is opened to an upper position in which the sleeve port passes entirely into the space between the cylinder wall and the depending head whereby said sleeve port is sealed during the compression and explosion strokes of the engine; means operated by the engine to raise air pressure, a carburetor fed with said air pressure and communicating with the intake port; grooves in the cylinder wall above and below said intake port, and a passage which supplies said air pressure to said grooves.

11. A valve mechanism, comprising a ported body with a bore, a valve movably fitted in the bore and controlling the body port; and means for maintaining fluid pressure around the port in the space between the valve and the surface of the bore.

12. A valve mechanism, comprising a body with a valve engaging surface and a port leading to said surface, a valve movable on said surface and controlling the port, and means for maintaining fluid pressure around the port in the space between the valve and said surface.

13. In a mechanism embodying a ported cylinder and a sleeve valve movably fitting within the cylinder and controlling its port, means to maintain an air pressure in the space between the sleeve and cylinder wall near the cylinder port, means to lubricate the sleeve at a zone below the port, and a relief groove located between the lubricating zone and the port.

In witness that I claim the foregoing I have hereunto subscribed my name this 19th day of August, 1921.

JOHN M. CAGE.
